CLAIM

I claim the ornamental design for a detachable girdle belt, as shown and described.

DESCRIPTION

FIG. 1 is a front elevational view of a detachable girdle belt showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof, shown in the detached configuration.
The broken lines representing stitching are part of the claimed design.**1 Claim, 8 Drawing Sheets**FIG.1
